UNITED STATES PATENT OFFICE.

OTTO J. KUHLKE, OF AKRON, OHIO, ASSIGNOR, BY MESNE ASSIGNMENTS, TO NATIONAL RUBBER MACHINERY COMPANY, OF AKRON, OHIO, A CORPORATION OF OHIO.

APPARATUS FOR VULCANIZING INNER TUBES.

Application filed March 10, 1928. Serial No. 280,877.

The object of this invention is to improve upon certain prior constructions of vulcanizers for inner tubes, or similar articles, such as shown and described, for example, in my 5 prior Patent No. 1,644,678, dated October 11, 1927.

In the prior patented construction, the machine as shown and described is adaptable for the manufacture of a single size of tube 10 or the like. The object of the present invention is to provide a mechanism which is adaptable for adjustment to different sizes of molds without necessitating a complete change of equipment. For this purpose, the 15 machine of the prior patent has been modified so as to make it readily adaptable for a large range of mold sizes as will be understood by those skilled in this art from the description which will be given. The manufacturer can 20 thus readily adapt his equipment for the varying demands as to sizes of tubes, and it is unnecessary to provide the multiplicity of units required with the earlier patented construction.

25 Briefly stated, the invention comprises an adaptor for use on a tube vulcanizer which will support varying sizes of molds. While the invention is illustrated as applied to the molding of tubes, it will be apparent that 30 it can readily be applied to the molding of flaps or other circular articles.

In the drawings in which the preferred form of the invention is shown:

Figure 1 is a front elevation of the improved tube vulcanizer showing the mold closed in full lines and open in dotted lines;

Figure 2 is a section on the line 2—2 of Figure 1;

Figure 3 is an enlarged elevation of that 40 portion of the adaptor plate located at the hinge with the molds removed; and

Figure 4 is a section on the line 4—4 of Figure 3.

The apparatus consists of the vertical up-right 45 1 which is supported on the base 2 and to the rear of which is secured an operating cylinder 4, the piston of which operates the vertical operating member 5. To the upper end of the upright 1 are pivoted horizontal shafts 6 to which are secured gear segments 8 each of which meshes with a rack formed in the side of the member 5, so that as the member is moved vertically, the gear segments are rocked. To these segments are secured

arms 9 and to the ends of the arms are pivoted 55 links 10.

In the prior construction, the movable mold elements were suspended directly from the ends of the links.

In the present apparatus, however, the 60 arms 10 are connected to arc-shaped adaptor plates 12 and 13. These plates are of sufficient width to receive the various sizes of molds for which the apparatus is adapted. The plate 12 is provided at its lower side with a 65 roller bearing 15, and the plate 13 with an extension 16 which overlies the lower end of the plate 12 and carries a pivot 18 receivable in the bearing 15 (Figure 4).

The hinged adaptor plates are supported 70 by a cam 20 attached to and forming an extension on the plate 12 and adapted to rest upon a roller 22 located on the base of the machine. A swinging, bifurcated link 24 pivoted to the plate 12, by shaft 25, and to a 75 pivot 26 on the base of the machine keeps the cam at all times in contact with the roller 22. When the rack 5 is lowered, the adaptor plates are raised and moved together, being held in locked position by a swinging link 80 28. When the rack is elevated, the adaptor plates are swung apart and lowered to the position shown in dotted lines in Figure 1.

The mold consists of an inner circular mold member and two outer mold members, 85 each of which is attached to an adaptor plate. The inner mold member is designated by the numeral 30 and is attached to the front of the upright 1 by brackets 32. The details of the mold need not be described as it is made substantially as shown in the prior patent, it being necessary merely to state that the brackets 32 on every size of mold are all alike 90 so that any size of mold is always centrally positioned with respect to the machine.

The movable mold members are designated at 34 and 35, the mold member 34 being carried upon the adaptor plate 12 and the member 35 in the plate 13. The mold members are pivoted by a transverse pin 36 in the member 34 and located in roller bearings 37 on the member 35. When the molds are mounted on the adaptor plates, the pin 36 is in alignment with the bearing pin 18 for the plates. The mold sections are attached to 100 the plates by single bolts passing through apertures 40 at the lower sides of the plates and by bolts through the properly selected 105

aperture of a group 41 at the upper ends of the plates. In this manner the hinge between the mold sections is kept in alignment with the hinge on the adaptor plates, while the varying sizes are taken care of by the plurality of openings at the top of the plates.

What is claimed is:—

1. An apparatus for curing tubes or the like, comprising a support, a stationary inner mold member on the support, a pair of plates carried on the support, said plates being pivotally connected, and a pair of outer mold members pivotally connected together, the pivot of the outer members coinciding with the pivot for the plates.
2. An apparatus for curing tubes or the like, comprising a support, a stationary inner mold member on the support, a pair of plates carried on the support, a pivotal connection

for said plates, outer mold members removably secured to said plates, operating mechanism attached to said plates and adapted to swing them about their pivots and thereby move the outer mold members to a position enclosing the inner mold members, and a pivotal connection between the outer mold members, said connection being coaxial with the pivotal connection between the plates.

3. In an apparatus for the uses and purposes set forth, a pair of plates pivotally connected together, outer mold members attached to said plates and pivotally connected together, and an inner mold member fixed with relation to the plates, said plates having means to hold varying sizes of mold members with their hinges always coaxial with the hinges of said plates.

OTTO J. KUHLKE.
